UNITED STATES PATENT OFFICE

126,983

DESIGN FOR A TIE RACK

Frank A. Lisi, Philadelphia, Pa.

Application February 15, 1941, Serial No. 99,018

Term of patent 14 years

To all whom it may concern:

Be it known that I, Frank A. Lisi, a citizen of the United States, residing in Philadelphia, county of Philadelphia, and State of Pennsylvania, have invented a new, original, and ornamental Design for a Tie Rack, of which the following is a specification, reference being had to the accompanying drawing, forming part thereof.

In the drawing:

Figure 1 is a side elevational view of the tie rack, showing my design. Figure 2 is an edge elevational view of the same.

I claim:

The ornamental design for a tie rack, substantially as shown.

FRANK A. LISI.
